UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK, A CORPORATION OF NEW YORK.

AUTOMATIC TRAIN-CONTROL SYSTEM.

Application filed May 24, 1919. Serial No. 299,488.

This invention relates to automatic train control systems for railroads.

One feature of this invention is the provision for automatically exerting pressure upon the engineer's brake valve handle at each caution signal, tending to move his brake valve to the service position, so that if the engineer is incapacitated, or for any reason fails to show that he is fully aware of the existence of danger ahead by taking hold of his brake valve handle and preventing its movement, an automatic service application of the brakes will be produced in the usual manner. This invention also contemplates the provision of automatic means for restoring the engineer's brake valve to the lap position, after it has been operated to the service position automatically, as soon as the desired reduction in brake pipe pressure has been made, thereby obviating any objections which may be incident to the continued venting of the brake pipe.

Another feature of the invention resides in the efficient and reliable means for establishing communication between the trackway and the moving car or train without physical contact between any parts on the track and the train, so that the operation of the system will not be influenced by snow, ice, or other adverse weather conditions.

Other specific objects and characteristics of the invention will appear hereinafter as the description progresses, and the novel features of the invention will be pointed out in the appended claims.

For the purpose of disclosing the nature of my invention, I have illustrated in the accompanying drawings, in a simplified and diagrammatic manner, some of the various forms of construction which the several devices and combinations of devices embodying my invention may take; and these constructions have been shown more with the view of making it easy to understand and appreciate the characteristic features of a system embodying my invention than with the view of illustrating the exact construction and arrangement of parts which would be preferably used in practice.

In describing the invention in detail, reference will be made to the accompanying drawings, in which like reference characters

refer to corresponding parts in the several views, and in which:

Figure 1 illustrates conventionally one arrangement of trackway circuits suitable for use as a part of my system of automatic train control;

Fig. 2 is a simplified and diagrammatic view, partly in section, which illustrates the construction of one form of brake controlling apparatus;

Fig. 3 illustrates diagrammatically one form of construction of the car-carried element and cooperating trackway element constituting the means for transmitting controlling impulses from the trackway to a passing train;

Fig. 4 illustrates a modification of the car-carried element shown in Fig. 3;

Fig. 5 illustrates still another construction of the car-carried element and the trackway element;

Fig. 6 is a side view of the car-carried element shown in Fig. 5;

Fig. 7 illustrates a still further modified construction of the car-carried element;

Fig. 8 is a fragmentary view illustrating a modified form of construction of the movable armature constituting part of the car-carried element shown in Fig. 7;

Fig. 9 illustrates another modification of the type of car-carried element shown in Fig. 7; and

Fig. 10 is a fragmentary view illustrating a still further modification of the construction shown in Fig. 7.

Considering first the trackway circuits shown in Fig. 1, the track rails 1 of the railroad track are divided by insulated joints 2 into blocks in the usual manner, one block B with the adjacent ends of two other blocks A and C being shown. Since the parts and circuits associated with the various blocks A, B and C are the same, they will be given, as a matter of convenience, the same reference characters with distinctive exponents. Each of these blocks is provided with a track battery 3 and a track relay 4, the same as in ordinary block signaling systems. Since my system of automatic train control is preferably used in connection with the usual fixed signals of the well known automatic block signaling systems, such signals S are indi-

cated conventionally in Fig. 1; but since the various circuits and devices governing the indications and aspects of these fixed signals are well known to those skilled in the art, 5 they have not been illustrated in order that the illustration might be simplified.

At an appropriate distance in the rear of the insulated joints 2 at the entrance to each block, (the normal direction of traffic being 10 from left to right as indicated by the arrow), is located a trackway element T, which cooperates inductively with a car-carried element to transmit the desired controlling influences or impulses to passing cars or trains. 15 The controlling circuit for this trackway element T, (which in the form illustrated in Fig. 1 includes a track battery 5), is controlled by a front contact of line relay 6. The controlling circuit for the line relay 6 includes 20 front contacts of the track relay of the corresponding block and also the track relay of the block next in advance, so that said line relay is energized when neither the corresponding block nor the next block in advance 25 is occupied, and is deenergized when either of said blocks is occupied, all in a manner which will be readily apparent to those skilled in the art.

The trackway circuits shown in Fig. 1 are 30 merely illustrative of a suitable arrangement by which the trackway elements of my automatic train control system may be controlled in the proper manner so as to transmit a cautionary impulse at each caution signal, or 35 stop signal, and not to transmit such an impulse at a clear signal. Obviously, various modifications and alterations may be made in the particular trackway circuits illustrated without departing from my invention, it being 40 evident that various expedients may be employed to obtain the desired opening and closing of the controlling circuit for the trackway element T in accordance with traffic conditions.

45 The train control apparatus which I preferably employ on the locomotive, motor cars, or other vehicles, is illustrated in a simplified form in Fig. 2, and comprises, generally stated, a pneumatic device which is set into 50 operation at each caution signal, by the de-energization of a controlling electro-pneumatic valve to exert a yielding pressure tending to operate the engineer's brake valve to the service position. The engineer's brake 55 valve being of well known construction is illustrated in a conventional form and is designated E. The pneumatic device for operating this brake valve may be attached to it in various ways, but in the construction illustrated, an arm 7 is fastened to the usual stem or shaft of the brake valve to which the engineer's brake handle or lever 8 is applied. A sector gear 9, integral with or attached to 60 the outer end of said arm 7, meshes with a rack 10, integral with or connected to, a rod 65

11, these various connections being preferably incased or constructed in such a manner that they cannot be readily taken apart maliciously by the engineer or other unauthorized person.

70 The rod 11 passes through one end of a cylinder D and loosely through a piston 12 in said cylinder, the right-hand end portion of the rod 11, as viewed in Fig. 2, being screw-threaded and provided with adjustable 75 clamping nuts 13, for the purpose hereinafter explained. Stops 14 are fixed to the inside of the cylinder D in position to limit the inward movement of the piston 12 toward the right, as viewed in Fig. 2. One end of the 80 cylinder D, at the left-hand side of piston 12, as viewed in Fig. 2, is in communication with the atmosphere through a device 15 of any suitable construction adapted to constitute an adjustable restricted orifice, and also 85 with a pressure supply pipe 16 leading to a control valve F. In the right-hand end of the cylinder D, is another piston 17, which has its movement toward the left limited by the stops 14 and which is provided with an adjustable 90 stop bolt 18 having a lock nut 19. The chamber in cylinder D at the right of piston 17 is in communication with the atmosphere, when said piston is at the left-hand extreme 95 of its movement, through an adjustable restricted orifice 20, and this chamber is connected to a supply pipe 21 leading to the control valve F.

99 The control valve F comprises a casing 22 and a differential piston 23. The larger end 100 of the differential piston 23 is in communication through pipe 24 with the usual brake pipe of the well known air brake system; and the smaller end of said differential piston is in 105 communication through pipe 25 with the main reservoir of the air brake system. The recesses and ports associated with the control valve F will not be specifically described, since they will be explained hereinafter in connection with the description of the operation 110 of the whole brake controlling device.

115 Whenever a caution signal is passed, an impulse is transmitted from the track to the train, in the manner hereinafter explained, to cause deenergization of an electro-pneumatic valve, hereinafter referred to as the E. P. V., which acts to supply compressed air from the main reservoir through an adjustable restricted orifice 26, a small expansion reservoir 27, and pipes 28 and 29 to the control valve F. In 120 addition to opening up communication in this manner, the electro-pneumatic valve E. P. V. is also of the type which, after having once been deenergized and unseated, cannot be re-closed upon energization of its controlling magnet until the pressure acting against the valve has been reduced to a predetermined amount. Various electro-pneumatic valves, 125 capable of performing the desired functions, are well known in the art, and the type of 130

valve illustrated, in Fig. 2 is merely illustrative of a construction suitable for use in my system of automatic train control.

As illustrated, this E. P. V. comprises a piston valve 30, which is normally held closed in the position shown by a stem 31 attached to the armature 32 of a controlling magnet 33, so as to cut off communication from a chamber 34, to which pipe 28 is connected, 10 through port 35 to chamber 36, to which pipe 29 is connected. When the magnet 33 is energized a valve 37 on its stem 31 opens communication from the enclosed chamber 36 to atmosphere through the exhaust port 38. 15 Upon deenergization of the magnet 33, the valve 30 and the stem 31 are forced downward by the pressure in chamber 34, this downward movement being also assisted by a compression spring 39 applied to the stem 31 20 in the usual manner.

The operation of the brake controlling apparatus just described need be only briefly explained. Normally the parts are in the position shown in Fig. 2. Upon deenergization 25 of the magnet 33 at the caution signal, valve 30 opens and valve 37 closes, thus supplying main reservoir pressure from expansion reservoir 27 through pipe 28, chamber 34, port 35, chamber 36, pipe 29, cavity 40, 30 port 41 in the differential piston 23, and pipe 16 to the cylinder D on the left-hand side of piston 12. This pressure forces the piston 12 over against the adjusting nuts 13, and thus exerts a pressure upon the rod 11 35 tending to operate the engineer's brake valve E to the service position. Unless the engineer, by holding his brake valve handle 8, prevents such movement, the piston 12 is forced over against the stops 14, thereby operating the brake valve E to the service position. 40 The adjusting nuts 13, together with the stops 14, permit the engineer's brake valve to be operated to the service position accurately. When the engineer's brake valve E is 45 operated to the service position, the brake pipe is vented in the usual manner to produce a service application of the brakes.

It will be noted that the area of the valve 50 30 exposed to pressure is greater when this valve is unseated than when it is closed; and consequently, said valve 30 cannot be reclosed by the magnet 33 until the pressure in chamber 34 has dropped to a predetermined amount, according to the size and proportion 55 of the parts. If the engineer does hold off the automatic brake application, the pressure in the cylinder D gradually falls to the point where the valve 30 can be reclosed by the magnet 33, (this magnet being only 60 momentarily deenergized, as explained hereinafter), by reason of the fact that the restricted orifice 15 is adjusted so as to be larger than the restricted orifice 26, so that air escapes to atmosphere through the orifice 15 65 from the expansion reservoir 27 and con-

nected pipes faster than it is supplied to said reservoir through the orifice 26. As soon as the valves 30 and 37 of the E. P. V. are restored to the normal position shown, the pressure in cylinder D and communicating pipes 70 is exhausted through passage 38, and pressure from the main reservoir builds up in the expansion reservoir 27, ready for the next operation. It will be observed that this construction provides for applying pressure to 75 the engineer's brake valve E for a limited time, this time interval being adjustable to best suit the requirements of an installation by varying the size of the restricted orifices 15 and 26, as well as selecting the size and 80 proportion of the parts. This time interval is preferably much greater than that required to vent the train pipe, so as to assure a full brake application.

It is intended that the pressure produced 85 by this brake controlling device upon the engineer's brake valve E will be sufficient to overcome the frictional resistance of said brake valve, but will not be so powerful that the engineer may not readily hold his brake 90 valve handle against movement. It should be noted that this construction does not interfere with the ordinary operation of the brake valve by the engineer. The rod 11 passes loosely through the piston 12 and permits the 95 engineer to operate his valve to the emergency position, as the occasion demands. Also, he may move his brake valve handle to the release position, if necessary, but in this instance, he will have to overcome the pressure 100 acting against the piston 12.

The brake controlling apparatus so far described merely serves to operate the engineer's brake valve to the service position. For reasons well understood by those skilled 105 in the art, it may be objectionable, however, to leave the brake valve in this service position for any great length of time; and I have also provided means for automatically restoring the brake valve E to the lap position 110 when the desired reduction in brake pipe pressure has been made. This is accomplished by the action of the differential piston 23. When the pressure in the brake pipe has been decreased to the desired amount 115 which corresponds to a predetermined fraction or ratio of a given pressure in the main reservoir, the pressure from the main reservoir through pipe 25 acting against the smaller end of the differential piston 23 over-balances the brake pipe pressure acting 120 against the larger end of said piston, and moves said piston to the right, as viewed in Fig. 2. This movement of piston 23 cuts off pressure from port 41 and opens pipe 16 to 125 atmosphere through cavity 42 and exhaust port 43. The pipe 21, which is normally in communication with the atmosphere through cavity 44 and exhaust port 45, is now placed 130 in communication with the pressure in expan-

sion reservoir 27 through cavity 40 and port 41. Thus, pressure is supplied to the right-hand side of piston 17, (which was moved to the right by the movement of rod 11), 5 and this forces the piston 17 to the left and causes the brake valve E to be restored automatically to the lap position. When the piston 17 attains its extreme left-hand position, the restricted orifice 20 is opened, there- 10 by gradually exhausting pressure from chamber 34 of the E. P. V., and permitting the piston valve 30 to reclose after a predetermined time. When the engineer recharges the brake pipe to release the brakes, the dif- 15 ferential piston 23 is automatically returned to the normal position shown.

This arrangement has the further advantage that the engineer will not be required to hold his brake valve handle 8, if he makes 20 an application of the brakes himself before passing the trackway element T at a caution signal. To illustrate, when the engineer reduces pressure in the train pipe to a predetermined amount, the differential piston 23 25 will move to its right-hand position, so that when the E. P. V. opens, pressure is not applied to the piston 12 to operate the brake valve E to the service position. In this way, if the engineer makes a full service brake 30 application before the E. P. V. opens, he is not required to hold his brake valve handle 8. As previously explained, the E. P. V. does not close until after a short time; and if the engineer releases the brakes within this limited 35 time after passing the caution signal, the differential piston 23 will return to its normal position and introduce pressure into the cylinder D against the piston 12. Thus, the engineer may avoid the trouble and annoy- 40 ance of holding his brake valve handle 8 by making an actual application of the brakes before passing a caution signal, but he cannot release such brake application until after the lapse of the time for which the 45 brake controlling apparatus is set. This timing may be varied as desired to best suit the special conditions in each instance by adjusting the restricted orifices 20 and 26.

The impulse transmitting means for controlling the magnet 33 of the E. P. V. may 50 take various forms. In the construction illustrated in Fig. 3, the trackway element T comprises a U-shaped permanent magnet 50 with side projections 51 which afford a leakage path for flux of lower reluctance than that between the pole pieces 52 of said permanent magnet. Surrounding the legs of the permanent magnet 50, and disposed above 55 projections 51, are oppositely wound coils 53 which are energized from the track battery 5 when the line relay 6 is energized. Thus, under clear traffic conditions, when the line relay 6 is energized, current is supplied to the coils 53, which are so wound as to produce a magneto-motive force opposing that

of the permanent magnet 50, thereby diverting this permanent flux through leakage paths, such as afforded by the projections 51. In short, the coils 53, when energized, act to substantially neutralize in effect the permanent flux of the magnet 50 so far as a field above the pole pieces 52 is concerned. Under dangerous traffic conditions, however, the coils 53 are open-circuited, and the permanent magnet 50 produces a magnetic field 75 emanating from its pole pieces 52.

The car-carried element L comprises two side members 54, which are arranged on the locomotive or passing vehicle, so as to pass directly over the pole pieces 52 of the trackway element T. The air gap between the pole pieces of the car-carried element L and the trackway element T is preferably made as short as practical clearances on railroads will safely permit. This air gap, however, 80 can readily be made large enough for all practical purposes by appropriately selecting the size and proportions of the various parts. The permanent magnets 50 are preferably located crosswise of the track, either outside 85 or between the track rails, as best suited to the particular conditions, and the side members 54 preferably extend lengthwise of the vehicle for a distance suitable to obtain the desired duration of an impulse. A magnetic 90 armature 55 is pivotally supported at one end to one of the side members 54; and this armature is biased by a spring 56, or equivalent means, away from the other side member 54, to the position illustrated in Fig. 3. In this 95 upper position of the armature 55, an insulated contact finger 57 carried thereby cooperates with suitable fixed contacts, indicated conventionally as arrows, and establishes a circuit for energizing magnet 33 of 100 the E. P. V.

The operation is as follows: When the car-carried element L passes over the trackway element T under clear traffic conditions, the de-magnetizing coils 53 being energized, 110 there is not sufficient flux through the side members 54 to overcome the bias of the armature 55, and the train may pass without operation of the E. P. V. Under dangerous traffic conditions, however, the flux produced by the permanent magnet 50 passes through the side members 54 of the car-carried element L, and causes attraction of the armature 55 against the opposition of the spring 56, thereby opening the circuit for the magnet 33 of the E. P. V. and setting the brake controlling apparatus into operation. 120

In the modification shown in Fig. 4, the side members 54¹ of the car-carried element are connected by a magnetic core 58, having 125 thereon a short-circuited coil or winding 59. The operation of this construction is substantially the same as that shown in Fig. 3, except that the attraction of the armature 55¹ is dependent upon the speed of the train past 130

the trackway element. This speed responsive feature of this construction is due to the core 58 and short-circuited coil 59. It will be evident that some of the flux transmitted from 5 the trackway element to the side members 54¹ will pass through the core 58, and since this flux changes during the approach and passage of the train past the trackway element, a current is induced in the coil 59, this current being, in accordance with well known 10 laws, of a direction to oppose the passage of flux through the core 58. The amount of this current induced, and the extent of its "bucking" action will be dependent upon the rate 15 of change of flux through the core 58, which in turn will depend upon the speed at which the train passes the trackway element. Thus, at high speeds, the passage of flux through the core 58 will be choked back so much that the 20 greater proportion will pass through the armature 55¹ and attract it to cause operation of the E. P. V.; but at low speeds, depending upon the size and proportion of the parts, so much of the total flux transmitted 25 from the trackway element will pass through the core 58 that there will not be enough flux through the armature 55¹ to overcome its bias.

In the construction illustrated in Figs. 5 30 and 6, the trackway element T¹ comprises two side members 60, angle-shaped in cross section, which are connected by a magnetic core 61 surrounded by a coil 62. These side members 60 preferably extend lengthwise of 35 the track for a sufficient distance to influence the car-carried element for a short interval of time suitable for producing a strong and reliable operation. If desired, a number of cores 61 and coils 62 may be employed with the side 40 members 60. The coil 62 is intended to be energized from a track battery under clear traffic conditions and to be deenergized under dangerous traffic conditions, as already explained. The car-carried element L¹ comprises two 45 cores 63, which are provided with pole pieces 64, and magnetizing coils 65. The cores 63 are supported in some suitable manner (not shown), so as to pass over the side members 60 of the trackway element T¹. Above the 50 cores 63 is pivotally mounted an armature 66. As illustrated, this armature 66 is provided with trunnion pins 67 at one edge which are held in adjustable bearings 68 carried by suitable fixed supports 69. The armature 66 55 is biased to its upper position away from the cores 63 by an adjustable counterweight 70, the downward movement of which is limited by a suitable fixed stop 71. The armature 66 also carries an insulated contact finger 72 60 adapted, when the armature is attracted downwardly against the opposition of its bias, to open the circuit controlling the E. P. V. The coils 65 are normally energized from a battery 73, or other source of 65 current, carried by the car; and included in

the energizing circuit of said coils, is a check relay 74 having a contact finger 75 and front contact included in the energizing circuit for the magnet 33 of the E. P. V. If the energizing circuit for the coils 65 should become 70 broken, or the battery depreciate, the contacts of the check relay 74 would open, thus operating the E. P. V. and calling attention to the fact that the system was out of order.

The parts of the car apparatus are so proportioned and adjusted that, when the train is traveling between the signaling points, the flux produced by the energizing coils 65 is not sufficient to attract the armature 66, this being due more particularly to the large air 80 gap between the pole pieces 64. Under clear traffic conditions, the coil 62 of the trackway element T¹ is energized to give the side members 60 a polarity (as indicated), which opposes the polarity of the pole pieces 64. As 85 a result, there is not a sufficient increase in the flux produced by coil 65 to attract the armature 66. Under dangerous traffic conditions, however, the trackway element T¹ presents to the car-carried element a magnetic 90 loop or bridge, so as to speak, which decreases the reluctance of the magnetic circuit through the coils 65 so much that, with the same current in said coils, sufficient flux is produced to attract the armature 66 and cause 95 operation of the E. P. V.

The modified construction of the car-carried element L², shown in Fig. 7, comprises an inverted U-shaped yoke 76 of magnetic material having pole pieces 77 arranged to 100 pass over the pole pieces of the cooperating trackway element. One leg of the yoke 76 is provided with two side extensions 78 and 79, constituting in effect a shunt path or bypass for flux through this leg of said yoke. 105 Arranged between the ends of these side extensions 78 and 79 is a movable armature, which in the construction illustrated, comprises a bar 80 of magnetic material integral with or attached to a block which is 110 yieldingly supported from the extensions 78 and 79 by light springs 81. This manner of support not only provides a bias to the armature 80, but also supports it so that it is less subject to movement by jar and vibration. The 115 armature 80 carries an insulated contact finger 82 adapted to open the energizing circuit for the E. P. V. On the leg of the yoke 76 between the extensions 78 and 79 is a short-circuited coil 83. On the other leg of 120 the yoke 76 is a coil 84 which is included in a normally closed circuit including a battery 85 and a check relay 86.

The check relay 86 is preferably of a balanced type which will cause operation of its circuit controlling elements when the current flowing in its coils is increased or decreased from a predetermined normal current for which the relay is adjusted. In the construction illustrated, the armature 87 of the relay 86 130

is biased by a spring, preferably adjustable, and is provided with a striking piece of insulating material which normally sets between two resilient contact springs 88. The 5 circuit for the E. P. V. is completed from one contact spring 88 through fixed contacts 89 to the other contact spring 88. By virtue of this construction, if the armature is attracted, or retracted by its bias, the circuit for 10 the E. P. V. will be opened by the movement of one or the other contact springs 88 away from the fixed contacts 89. The strength of the battery 85, and the resistance of the coil 84 and the check relay 86, are so selected that, 15 under normal conditions, the attraction exerted by the flow of current in the check relay 86 just balances its bias, thereby keeping the circuit for the E. P. V. closed. If the current through the relay 86 decreased below its 20 normal flow, due to a breaking of the circuit, or depreciation of the battery 85, the bias of the armature 87 will overcome the tractive force of the windings of said relay, and thus open the E. P. V. circuit. Likewise, if the 25 current is increased above the predetermined normal value, due to a cross or the like, the armature 87 will be attracted and will break the E. P. V. circuit. In short, the check relay 86 detects any failure of the circuit for energizing the coil 84, either by breaks or crosses.

The car-carried element L² shown in Fig. 7, may be used in connection with any one of the various types of trackway elements illustrated; and when used with the trackway 35 element T¹ shown in Fig. 5, for example, the operation is as follows: Under clear traffic conditions, the coil or winding of the trackway element is energized to present pole pieces of a polarity opposite to the polarity 40 given to the pole pieces 77 of the car-carried element L² by the current flowing in the coil 84, so that there is little, if any, change in the flux through the yoke 76. Under dangerous traffic conditions, the trackway element 45 presents in effect a dead magnetic loop which greatly reduces the reluctance of the magnetic circuit through the coil 84, so that with the same current flowing through this coil, a much greater flux passes through the 50 yoke 76. This change in the flux through said yoke 76 induces a current in the short-circuited coil 83, which opposes the passage of flux through this leg of the yoke and causes some of it to be diverted through the extensions 55 78 and 79 and the armature 80, thereby exerting an attraction upon said armature 80 and moving it against the biasing force of the springs 81 to open the circuit for the E. P. V.

In the modified construction illustrated in 60 Fig. 8, an armature 90, of the Z-type, is employed instead of the single bar armature 80 shown in Fig. 7. The armature 90 is supported by the springs 91 in substantially the same way as the armature 80, and carries an 65 extension 92 adapted to separate the con-

tacts included in the circuit for the E. P. V. This construction operates in substantially the same way as hereinbefore described in connection with Fig. 7; but on account of the use of a Z-armature, the tractive force 70 upon the armature is exerted for a much greater range of movement, thereby permitting the parts to be arranged so that said armature may have a considerable idle movement before actuating its contacts. This aids 75 in obviating any difficulty incident to the vibration of the armature 90 by the jars and shocks to which it would naturally be subjected when carried on a train.

The construction illustrated in Fig. 9 is 80 substantially the same as that shown in Fig. 7, the principal difference being that a permanent magnet 93 is employed in place of the yoke 76 and magnetizing coil 84, thereby dispensing with the coil 84, battery 85, 85 and check relay 86. This construction operates in the same way as previously described.

In the construction illustrated in Fig. 10, an armature 94 of the shuttle type is mounted between the curved pole faces of the extensions 90 78² and 79², and the windings 95 of this armature are connected in closed circuit with the coil 83². The armature 94 is provided with an arm 96, carrying a contact finger 97 for controlling the controlling circuit of the E. P. V.; 95 and a spring 98 is connected to said arm 96 and to a suitable fixed member so as to exert a biasing force tending to hold said armature in its normal position, shown in Fig. 10. The various parts, including the inductance of the coil 83² and the windings of the armature 94, are so selected that the current in the windings of said armature will, when the flux is sent through the yoke 76², as previously explained, be substantially in 100 phase with that passing through the extensions 78² and 79². In this way, in addition to the torque exerted upon the armature 94 by virtue of the flux through said extensions 78² and 79², the current induced in coil 83² 110 assists in actuating said armature by passing through the windings thereof and creating a field in cooperative relation with the field of flux between the pole faces of said extensions. 115

The various modifications in the construction of the car-carried element and the trackway element, illustrated on the accompanying drawings, are merely typical and illustrative of the various forms embodying my invention, and various other constructions and 120 combinations involving the same principles and characteristics will be readily apparent to those skilled in the art. I desire it to be understood, therefore, that the constructions illustrated do not exhaust the various modifications which may be made in accordance with my invention. Those types of car-carried elements which include a magnetized yoke, or equivalent magnetic circuit, on the 125 car, such as shown in Figs. 5 to 10, may be used 130

with a trackway element of any one of the types shown in Fig. 3, or Fig. 5, the appropriate size and proportion of parts being, of course, selected for each combination for the best practical results. Furthermore, it is obvious that the various types of impulse transmitting means herein disclosed may be used with various forms of train control or brake governing appliances, and I desire to have it understood that my invention in this, as in many other respects, is not limited to the precise constructions and combinations of various devices illustrated and described.

What I claim as new and desire to secure by Letters Patent of the United States, is:—

1. In an automatic train control system, the combination with the air-brake system of a railway vehicle, of automatic brake applying means operable to act upon the air-brake system and to cause an automatic application of the brakes, said brake applying means including a manually operable element by which the engineer may prevent its operation, control means which if actuated operates said brake applying means, means partly on the vehicle and partly on the track cooperating inductively through an intervening air-gap for actuating said control means at predetermined control points along the track under unsafe traffic conditions ahead, and automatic means effective only if the brakes are manually applied to a predetermined degree by the engineer prior to the actuation of said brake applying means for preventing initial operation thereof even though said control means is actuated.

2. Inductive impulse communicating means for train control systems comprising, a track element providing spaced magnetic poles of opposite polarity in its active stopping condition, traffic controlled means for rendering said track element ineffective, a car-carried receiver comprising a partial magnetic circuit arranged to receive the magnetic flux emanating from said active track element, said partial magnetic circuit including two magnetically separated paths in multiple, flux responsive circuit controlling means magnetically associated with one path, and a winding on closed circuit magnetically associated with the other path.

3. A car-carried impulse receiving element adapted to respond to magnetic flux transmitted thereto from the trackway, comprising means affording two partial magnetic circuits in multiple, and normally closed circuit controlling means jointly controlled by the rate of change and intensity of flux in said partial magnetic circuits.

4. In an automatic train control system, the combination with a track element constituting a magnet in the active stopping condition, a car-carried receiver adapted to cooperate with said magnet, said receiver hav-

ing two flux paths in multiple, a biased armature magnetically included in one path, a winding magnetically associated with the other path, a brake control device, a normally energized circuit for maintaining said device inactive, and contacts in said circuit opened by a movement of said armature in opposition to its bias.

5. In an automatic train control system, the combination with the air-brake system of a railway vehicle; of an automatic brake setting device acting upon the air-brake system to vent the brake pipe pressure to an amount representing a predetermined ratio of a pre-selected pressure; control means when actuated operating said brake setting device; automatic means for actuating said control means at predetermined control points along the track when dangerous traffic conditions exist; and means responsive to the drop in brake pipe pressure, and effective only if the engineer reduces said brake pipe pressure to at least the same ratio and prior to the actuation of said device, for preventing initial operation thereof even though said control means is actuated.

6. A train control system for railroads comprising, in combination with the air-brake system of a railway vehicle, of automatic brake applying means on the vehicle operable to act upon the air-brake system and cause an automatic brake application; means effective only if the engineer manually applies the brakes to a predetermined degree prior to the operation of said means for preventing initial operation thereof irrespective of the speed of the vehicle; a traffic controlled trackway element; a receiver on the vehicle cooperating with said trackway element and having a partial magnetic circuit and a biased armature, said armature being magnetically moved in opposition to its bias by the trackway element in its active stop condition, and a normally energized circuit opened by said movement of said armature for controlling said brake applying device.

7. A car carried impulse receiving element for automatic train control systems comprising a core constituting a partial magnetic circuit with two multiple paths, a biased movable armature in one path, and a short-circuited coil associated with the other path.

8. A car carried impulse receiving element for automatic train control systems comprising means constituting a partial magnetic circuit with an air gap, a movable armature associated with said magnetic circuit, a winding magnetically associated with said armature, and means responsive to a change of flux in said magnetic circuit for energizing said winding.

9. A car carried impulse receiving element for automatic train control systems comprising a magnetic core, circuit controlling means

magnetically associated with said core, and responsive to the rate of change of flux therein, whereby the operation of said circuit controlling means is dependent upon the speed 5 of the car.

10. In an automatic train control system, the combination with the air-brake system of a railway vehicle, of a brake setting device operable automatically to act upon the air-brake system and produce a brake application, means partly on the vehicle and partly on the track for imparting a control impulse to the vehicle at predetermined control points when danger traffic conditions exist, apparatus on the vehicle responding to said impulses and tending to operate said brake setting device for a time and irrespective of the running speed of the vehicle, and means effective only if the engineer manually applies the 15 brakes to a predetermined degree prior to the operation of said brake applying device for preventing initial operation thereof and for continuing such prevention so long as the manual brake application is in effect irrespective of the speed of the vehicle.

11. A train control system comprising, in combination, the air-brake system of a railway vehicle, a device operable to vent the brake pipe of said air-brake system, automatic means responding to the drop in brake pipe pressure for placing said device in condition to arrest further venting of the brake pipe after the pressure therein has been reduced to a predetermined extent, said means 30 responding to the reduction in brake pipe pressure upon a manual application of the brakes and acting automatically to prevent initial operation of said brake applying device, only if and provided the reduction in brake pipe pressure by such manual application is to the same or greater degree and occurs prior to the operation of said device.

12. In a train control system, the combination with inductive impulse communicating means including a track element constituting an inert body of iron when in its active stopping condition, said track element having a coil acting when in a closed circuit to render said element inactive, of brake control apparatus governed by said means and comprising, brake applying means tending to cause an automatic brake application, and means effective only if the brakes are manually applied by the engineer to a predetermined degree prior to operation of said brake applying means for preventing the initial operation thereof.

13. In a train control system, the combination with a track magnet having opposite poles located along the track, of a car element having a partial magnetic circuit with an air gap, a biased armature spanning the air gap, means forming a flux path of high reluctance around said armature when the

car element passes over the track element, 65 train control apparatus on the car, and circuit controlling means actuated by said armature for governing said apparatus.

14. In a train control system, the combination with a track element constituting a magnet when in the stopping condition, of a car element for receiving flux from the track element, said car element comprising a biased armature and having an iron flux path in multiple with said armature, and a coil in 70 closed circuit associated with said flux path and adapted to increase the reluctance of said path when the car element passes over the track element.

15. A car element adapted to respond to 80 magnetic flux transmitted from the trackway and having two partial magnetic circuits in multiple, a biased armature in one of said circuits, a coil in closed circuit included in the other of said circuits, and circuit controlling means actuated by said armature.

16. In a train control system, the combination with a track element constituting a magnet when in the stopping condition, of a car element provided with two flux paths 90 in multiple, a coil associated with one path and in which current is generated when the car element passes over the track element, and circuit controlling means associated with the other path and having its operation dependent on the flux in that path and also on the current generated in said coil.

17. In an automatic train control system, the combination with fluid pressure operated means for automatically applying the brakes 100 by venting the brake pipe, control means for controlling the flow of fluid pressure to said fluid pressure operated means to effect such venting under adverse traffic conditions ahead, and means for controlling the flow of fluid pressure between said control means and said fluid pressure operated means to cause or arrest venting of the brake pipe depending upon whether the brake pipe has already been vented to a predetermined extent either manually or automatically.

18. In an automatic train control system, the combination with fluid pressure operated means for effecting an application of the brakes of the train by venting the brake pipe, 115 control means for controlling the flow of fluid pressure governing said fluid pressure operated means and effective to cause said fluid pressure operated means to vent the brake pipe under adverse traffic conditions ahead, and differential piston means having opposing pressures acting thereon one of which is a fixed pressure and the other of which is brake pipe pressure for controlling the flow of fluid pressure between said fluid pressure means and said control means.

19. In an automatic train control system, the combination with fluid pressure operated

means for applying the brakes of the train by venting the brake pipe thereof, control means for controlling the flow of fluid pressure for controlling the fluid pressure operated means to effect such venting under adverse traffic conditions ahead, and differential piston means for controlling the flow of fluid pressure between said control means and said fluid pressure operated means to determine venting of the brake pipe depending upon whether the brake pipe has already been vented to a predetermined extent either manually or automatically.

WINTHROP K. HOWE.
